[57] CLAIM

The ornamental design for a vacuum bottle holder, as shown and described.

DESCRIPTION

FIG. 1 is a front perspective view of a vacuum bottle holder showing my new design.

FIG. 2 is a side elevational view, partly in section with a portion of the handle omitted.

FIG. 3 is a top view thereof, and

FIG. 4 is a bottom view thereof.

The side opposite that shown in FIG. 2 is a mirror image of the side shown and the rear view is unornamented.
